UNITED STATES PATENT OFFICE.

RICHARD J. WELTON, OF FORT MORGAN, COLORADO.

DRAWING-BOARD.

1,049,015.

Specification of Letters Patent. Patented Dec. 31, 1912.

Application filed January 18, 1911. Serial No. 603,309.

To all whom it may concern:

Be it known that I, RICHARD J. WELTON, a citizen of the United States, residing at Fort Morgan, in the county of Morgan and 5 State of Colorado, have invented new and useful Improvements in Drawing-Boards, of which the following is a specification.

This invention relates to drawing boards and the object of the invention is to provide 10 a collapsible board which may be knocked down and packed in a small space for convenient transportation.

A further object of the invention is the provision of a knock down board having a 15 metallic supporting frame which is also knock down and which when connected together will provide a perfectly true edge to serve as a guide for the T-square and other instruments.

20 A further object of the invention is the provision of a detachable drawer to be used in connection with the board when the same is used for office purposes. The board is especially designed for photographers, field 25 engineers or any case where drafting is required to be done in the field or at points distant from the office.

Further objects of the invention will appear as the following specific description is 30 read in connection with the accompanying drawing which forms a part of this application, and in which:

Figure 1 is a top plan view. Fig. 2 is a detail horizontal section. Fig. 3 is a section on the line 3—3 of Fig. 1. Fig. 4 is a section on the line 4—4 of Fig. 2. Fig. 5 is an edge elevation with parts broken away and with the drawer and drawer supporting cleats in section.

40 Referring more particularly to the drawing 1 represents the frame of the device which is constructed of the side members 2 and the end members 3. Both the side and end members are preferably constructed of 45 stamped sheet steel, brass or the like and are provided with a plurality of apertures 4 which are cut out of the metal to lighten the same and to prevent any unevenness of the board by expansion or contraction. The 50 outside edges of the side and end members are provided with a downwardly extending flange 5 and the ends of each of said members are provided with flanges 6 which are

arranged diagonally across said members so as to form a miter joint between the same. 55 The flanges 6 are apertured to receive the connecting bolts 7 whereby the side and end members may be secured together in rectangular form as shown in Fig. 1.

The inner edges of the side and end members have secured beneath the same by means of countersunk screws or rivets 8, substantially Z-shaped strips 9 which form the bored rabbet 10 extending entirely around the frame and adapted to receive the reduced 60 ends of the boards 11. These boards are preferably tongued and grooved so as to hold the boards flush with the upper edge of the frame throughout their length. Soft pine or other similar woods are used to construct 70 the boards of and each board is preferably about four or five inches wide so that they will not occupy much space when packed together.

As shown in Fig. 5, there is attached to 75 the underside of the board a pair of drawer cleats or strips 12 which are adapted to receive the overhanging flanges 13 of the drawer 14 which is also preferably constructed of stamped up metal. It will be seen that 80 by constructing a board in this manner, I am enabled to produce a board which may be readily knocked down so as to occupy small space for transportation and one which will present a perfectly true surface for drawing 85 instruments at all times. The top or face of the side members is preferably nickelized or otherwise treated so as to present a pleasing appearance.

Having thus described the invention, what 90 is claimed is—

1. In a drawing board, a frame comprising metallic side and end members, each having flanged and mitered ends, means to removably connect the mitered ends of the 95 side and end members so as to produce a rectangular frame, a rabbet strip carried by each of said side members, and a sectional board mounted on the rabbet strip and abutting the inner edges of the frame members. 100

2. In a drawing board, a frame comprising metallic side and end members, each having flanged and mitered ends, means to removably connect the mitered ends of the side and end members to produce a rectangular 105 frame, Z-shaped rabbet strips secured to the

under side of the side members, a sectional board having its ends rabbeted to seat beneath the side members on the rabbet strips and to abut the inner edges of the frame members, drawer supporting cleats carried on the under side of the end members, and a 5 drawer slidably mounted therein.

In testimony whereof I affix my signature in presence of two witnesses.

RICHARD J. WELTON.
